UNITED STATES PATENT OFFICE.

THOMAS I. RANKIN, OF PHILADELPHIA, PENNSYLVANIA, ASSIGNOR TO THE
ABRAM COX STOVE COMPANY, OF SAME PLACE.

DESIGN FOR A HEATING-STOVE.

SPECIFICATION forming part of Design No. 34,909, dated August 6, 1901.

Application filed September 8, 1900. Serial No. 29,464. Term of patent 7 years.

To all whom it may concern:

Be it known that I, THOMAS I. RANKIN, a citizen of the United States, residing in Philadelphia, Pennsylvania, have invented and produced a new and original Design for Heating-Stoves, of which the following is a specification.

My design for a heating-stove is fully illustrated in the accompanying drawing, which represents a stove in perspective.

The essential feature of the design is the peculiar form of scrollwork on the body of the stove.

A is the quadrangular body of the stove.

15 B is the base, and C is the cover-plate or top, of the stove.

The body A of the stove is quadrangular, and at each corner are columns *a a*, having leaf designs thereon. The upper portion of 20 the body is extended at *a'*, and on these extended portions are S-scrolls, and at each corner they form a bead-scroll rosette. Under these rosettes are scrolls.

The fire-door *c* has a central rosette and scrolls, and leaf-scrolls make up the body of the door. Above the door is a curved rib with scrolls within the arch. The panel *a*, 25 below the fire-door, has two main scrolls, from which extend numerous branches, as shown.

30 The side panels E of the stove are in keeping with the general design of the front panels.

The ash-pit door *f* has two circular projections, one at each side of the center, and above the projections are small rosettes, and between these rosettes is a fan-like design. The 35 design of the portion of the body surrounding the ash-pit has scrollwork in keeping with the scrollwork at the upper portion of the body.

The base of the stove B is supported on 40 legs, and extending from one leg to the other is a ribbon-scroll, from which projects intricate leaf-scrolls. At each foot there are leaf-scrolls mounted within the scroll framework. The foot-rests *i i* at each side are ornamented 45 to correspond with the general ornamentation of the stove.

The top or cap plate C of the stove has a design in keeping with the body of the stove.

I claim—

The design for a stove as herein described and as illustrated in the accompanying drawing.

In testimony whereof I have signed my name to this specification in the presence of 55 two subscribing witnesses.

THOMAS I. RANKIN.
